UNITED STATES PATENT OFFICE.

BUELL S. BURNETT, OF JACKSONVILLE, FLORIDA.

PERMUTATION-LOCK.

1,197,443.

Specification of Letters Patent. Patented Sept. 5, 1916.

Application filed November 10, 1915. Serial No. 60,773.

To all whom it may concern:

Be it known that I, BUELL S. BURNETT, a citizen of the United States, residing at Jacksonville, in the county of Duval and State of Florida, have invented new and useful Improvements in Permutation-Locks, of which the following is a specification.

This invention relates to improvements in permutation locks.

10 The invention consists in improvements in the organization of the lock casing and the operating parts carried thereby or associated therewith, the stem by which said parts are operated, and the rotatable controlling element which is operatively connected by the said stem to the said operating parts, the objects of such improvements being to enable certain specific applications of permutation locks, such, for example, as the 20 application of a permutation lock to slot or coin-controlled machines; and to promote facility in effecting changes of the combination.

25 The invention also consists in specific improvements in the organization of the operating parts of the lock having for their object a simple, compact, inexpensive and reliable permutation lock structure.

An embodiment of the invention is shown 30 in the accompanying drawings, wherein the invention is disclosed in its application to the cash boxes of coin-controlled gas meters.

In the said drawings: Figure 1 is an elevation showing the lock dial operatively applied; Fig. 2 is an elevation showing the operating parts of the lock with the bolt retracted; this figure pre-supposes the removal of the back plate; Fig. 3 is a view similar to Fig. 2 but showing the bolt projected; certain parts are omitted from this figure to expose to view the main tumbler; Fig. 4 is a 40 central vertical sectional view showing the bolt projected; Fig. 5 is a similar view showing the bolt retracted; Fig. 6 is an elevation of that side of the lock casing to which the bolt is applied; Fig. 7 is a horizontal sectional view on the line 7—7 of Fig. 4; Fig. 8 is a detail perspective view of the lock casing, looking at the side thereof to which the bolt is applied; and Fig. 9 is an elevation showing the rotatable controlling element to which the dial and the operating knob are applied.

Similar characters of reference designate 55 corresponding parts throughout the several views.

As above stated, the lock is shown in its application to the cash box of a coin-controlled gas meter. The front wall of this cash box is shown at 1 and the coin receptacle is shown at 2. The cash box as an entirety is fitted against a side wall of the meter, which said side wall has a hook-like lug or keeper 3 which projects into the cash box adjacent the lower end thereof and 65 which is engaged by the bolt of a lock, the lock being arranged under the coin receptacle 2. So far nothing new has been described.

The lock disclosed is of the general construction shown by my U. S. Patents No. 1,136,653 of April 20, 1915, and No. 1,163,504 of December 7, 1915, although it has certain specific improvements in the organization of the operating parts to which certain 75 of the appended claims are directed.

The lock casing, indicated generally at 4, consists of a base plate 5 provided with an annular flange 6 which is preferably of flaring or frusto-conical form and a group of 80 superposed rings 7, 8 and 9 which are connected to said base plate and are arranged at that side thereof opposite to the side from which the flange 6 projects. The operating parts of the lock comprise a disk-like main 85 tumbler 10 with which is associated a plate 11 having diametrically opposite co-planar projections 12, and a pair of annular tumblers 13 and 14 which, for convenience, may be termed "ring" tumblers. The parts 10, 90 11, 13 and 14 are exactly similar to and co-operate in the same manner as the respective parts 12, 29, 14 and 15, as shown in my said Patent No. 1,163,504. Therefore, only a general description of these parts is 95 required. The ring 8 is of greater width than the rings 7 and 9. The ring tumbler 13 fits between the ring 8 and the base plate 5 in co-planar relation to the ring 7. The ring tumbler 14 fits between the ring 8 and 100 the back plate 15 in co-planar relation to the ring 9. The main tumbler 10 is disposed within an opening in the base plate 5 in co-planar relation to said base plate and the plate 11 fits against the base plate 5 in co-planar relation to the tumbler 13.

The tumbler 10, of which the plate 11 with its projections 12 is functionally a part, and the tumblers 13 and 14 control the operation of a sliding bolt 16, which, according 110 to the present embodiment, is fitted against the front face of the plate 5 and within the

flange 6, and which includes a bolt head 16^a and an extended shank 16^b formed with a longitudinal slot 16^c and with a forwardly directed terminal projection 16^d for engagement by a spring 17 which effects the retraction of said bolt. According to the present invention the shank of the bolt is of less thickness than its head and the projection 16^d over-hangs that portion of the head 5 which projects laterally beyond the shank. The said projection 16^d and the head bear against a plate 34 to be hereafter referred to and provide between them a clearance into which the spring 17 projects. The bolt 16, 10 except for its arrangement adjacent the inner face of the plate 5 and the provision of the shank 16^b, is generally similar to the bolt 7 shown in my said Patent No. 1,163,504 and includes a pointed projection 16^e which 15 engages the margin of the tumbler 10 and a second projection 16^f which co-acts with the tumblers 13 and 14. The flange 6 is provided with a recess 18 through which the bolt 16 works and the base plate 5 is provided with a radial slot 19 through which the projections 16^e and 16^f extend. The rings 7, 8 and 9 are provided with the alining recesses 20 in which the projection 16^e enters when the bolt is projected. The tumbler 10 has a radial recess 21 of general V 20 form which extends from the central opening of the tumbler to the annularly curved margin thereof and in which the projection 16^e enters when the bolt is retracted; said 25 projection, when the bolt is extended, riding and bearing upon the said annularly curved marginal portion of the tumbler 10. To project the bolt 16, the tumbler 10 is rotated in either direction from the position 30 shown in Fig. 5 and in dotted lines in Fig. 2, and in accordance with its direction of rotation, either of the inclined sides of the recess 21 will engage the projections 16^e and, 35 exerting a cam action thereon, will project the bolt in the obvious manner.

As shown, each of the tumblers 13 and 14 has a pair of marginal recesses 22 which are exactly similar in purpose, arrangement and operation to the recesses 32, 33, 34 and 35 50 of the tumblers 14 and 15 disclosed in my said Patent No. 1,163,504. The main tumbler 10 operates the ring tumbler 13 through the engagement of the projections 12 (which are functionally a part of said main tumbler) 55 with projections 23 located at opposite points of the inner circumference of said ring tumbler and the ring tumbler 13 operates the tumbler 14 through the engagement of its projections 23 with projections 60 24 located at opposite points of the inner circumference of the tumbler 14 and projecting inwardly, *i. e.* toward the base 5. The bolt is retracted by its spring 17 when there is a coincidence of a recess 22 of each 65 of the tumblers 13 and 14 and a simulta-

neous radial alinement of said coinciding recesses with the recess 21 of the tumbler 10 and with the projections 16^e and 16^f of the bolt 16. The operations of alining and disalining the tumblers are effected by a rotation of the main tumbler 10, precisely as disclosed in my said Patent No. 1,163,504. 70

According to the present invention, the controlling element of the lock is rotatably mounted with relative permanency in the 75 wall or an equivalent part adjacent which the lock is applied. As shown, this controlling element, designated generally by the numeral 25, is rotatably mounted in the wall 1 and consists of three superposed 80 plates connected by rivets or otherwise, the middle plate being of less diameter and functioning as a journal, and fitting in an opening in the wall 1. According to the present invention, a detachable operating 85 connection is interposed between the operating parts which are carried by the casing and the controlling element 25. This connection, as shown, consists of a flat-sided (preferably octagonal) stem 26 which fits in 90 a conforming opening in the element 25 and which projects through conforming openings in the tumbler 10 and plate 11. A head 27 is mounted upon the end of the stem 26 which projects beyond the plate 11, said 95 head being preferably loosely mounted and being confined between the plate 11 and the back plate 15. The stem 26 also projects through the slot 16^c of the bolt shank 16^b, forming a 100 guide for the inner portion of the bolt, complementary guides being provided by lugs 28 which are struck up from the plate 5 and engage the outer side faces of the shank 16^b. 105

The dial 29 and the operating knob 30 integral therewith may be connected either 110 permanently or detachably to the controlling element 25. As shown and preferred, said dial is detachably connected to said controlling element, being provided with a pair of pins 31 which engage openings 32 formed 115 in the element 25. The wall 1 has an inwardly dished portion 33 surrounding the controlling element 25 whereby the outer face of said element comes flush with the outer face of the wall and when the dial 29 is applied to rotate the controlling element, said dial fits uniformly against the face of the wall 1 outside of the dished portion 33, as clearly shown in Fig. 4. 120

The advantage of making the dial detachable from the controlling element and of operatively associating the dial with said element through the projections 31 or their equivalent is that one dial may be assigned to an operator having charge of a number of locks, say five hundred, whose combination is the same. By arranging the pins 31 at relatively different points on the different dials which are assigned to the various operators, it will be impossible for an oper- 125 130

ator to work the particular combination of his locks except with the particular dial which is assigned to him. Assuming, for example, that the combination of a particular group of locks is 36, 28 and 17 and can be worked with the pins 31 in a certain position relatively to the dial; if another dial be substituted having said pins arranged in another position relatively to its bars, turning movements of the dial to bring the numbers 36, 28 and 17 successively under the pointer will not work the combination, as is obvious. In this way, the detachable relation of the dial to the controlling element 25 in conjunction with the operative connections between said dial and said controlling element, enables the dials to be differentiated from one another, whereby attempts at fraud will be thwarted.

The advantage of the detachable relation between the stem 26 and the controlling element 25 lies in the facility thereby afforded for changing the combination of the lock. By removing the plate 15 and pulling the stem 26 rearwardly (without, however, disengaging it from the tumbler 10 and plate 11) said stem may be withdrawn from the opening in the controlling element 25 and said element may thereupon be rotated into another position, at which time the stem 26 is reinserted. This rotation of the controlling element 25 when the stem is withdrawn will establish a different relation between the tumblers on the one hand and said element and the dial on the other hand, as is obvious. The number of changes of combination which can be effected by thus rotating the element 25 depends upon the number of flat sides with which the stem 26 is provided. Where said stem is octagonal, eight changes of combination, by rotation of the element 25, are possible. Other changes of combination may be effected by varying the relative positions of the tumblers 10, 13 and 14, in the manner explained at length in my said Patent No. 1,163,504 and for each different relation of the tumblers 10, 13 and 14, eight changes of combination may be made by rotatable adjustment of the controlling element 25 relatively to the stem 26 in the manner explained. The withdrawal of the stem 26 from the controlling element 25 to permit the adjustment of the latter relatively to said stem does not disturb the relation of said stem to the tumbler 10 and plate 11. If desired, however, said tumbler and plate on the one hand and said stem on the other hand may be disengaged from one another, the stem having a slideable fit in the openings of the tumbler 10 and plate 11, and being capable of complete withdrawal or disengagement from said openings.

In the application of the lock to cash boxes similar to that disclosed, a rest plate

34 is provided against which the flange 6 bears, said plate having an opening for the stem 26. The plate 34 is provided with corner lugs 35 which are secured by screws or rivets to the wall 1. The lock casing 70 and the operating parts are held in place by fastening screws 36 which take into the rest plate 34 and extend through openings in the back plate 15 and in the rings 7, 8 and 9 and base plate 5.

That feature of the invention which involves the detachable relation among the lock proper, the stem 26, and the controlling element rotatably mounted in a wall of the structure to which the lock is applied obviously does not require for its practice the particular lock construction disclosed, but may be practised in connection with other locks wherein the stem constitutes an operative connection between the said controlling element and a rotatable member of the lock organization by which the projection and retraction of the bolt is controlled.

It is to be understood that no specific description herein contained is intended to put any limitation upon the scope of the appended claims which does not inhere in the language thereof.

Having fully described my invention, I claim—

1. In a permutation lock, in combination, a slideable bolt provided with inner and outer projections, a main tumbler having a marginal recess to co-act with the inner projection, a plurality of ring tumblers having marginal recesses to co-act with the outer projection, a dial-operated rotatable controlling element having a polygonal recess, the main tumbler having a polygonal opening, a polygonal stem forming an operative connection between the controlling element and the main tumbler and being disengagable by a sliding movement in the direction of its axis from either of said parts, said stem, upon its disengagement from either of said parts, being rotatably adjustable relatively thereto, the ring tumblers having central openings of greater diameter than said stem through which the stem extends, said ring tumblers having the margins of their central openings provided with inter-acting projections, and a member having a polygonal opening and conformably fitted on said stem, said member being provided with radial projections for engagement with the projections of one of said ring tumblers.

2. The combination in a permutation lock of a slideable bolt provided with a slotted shank and with outer and inner projections, a base plate which the bolt adjoins and which is provided with an enlarged central opening, a main tumbler fitted in said opening and having a marginal recess for co-operation with the inner projection, a plu-

rality of ring tumblers arranged at the side of said base plate opposite said bolt and provided with marginal recesses for cooperation with the outer projection, a rotatable controlling element, a stem operatively connecting said controlling element and said main tumbler and extending through the slot in said shank, the ring tumblers having central openings through which the stem extends and having the margins of said openings provided with interacting projections, and a part fitted on the stem and provided with radial projections for co-operation with the projections of one of said ring tumblers.

3. The combination of a permutation lock having a casing provided with a base plate, a slideable bolt arranged adjacent one face of said plate and having a slotted shank, and tumblers arranged adjacent the other face of said base plate and controlling the projection and retraction of said bolt, a rotatable controlling element and a stem operatively connecting said controlling element and said tumblers and extending through the slot in said shank.

4. The combination of a permutation lock having a casing provided with a base plate, a slideable bolt arranged adjacent one face of said plate and having a slotted shank, and tumblers arranged adjacent the other face of said base plate and controlling the projection and retraction of said bolt, a rotatable controlling element, said bolt being arranged intermediate said base plate and said controlling element and a stem operatively con-

nected said controlling element and said tumblers and extending through the slot in said shank.

5. The combination of a permutation lock including a base plate, a slideable bolt arranged adjacent one face of said plate and having a slotted shank, a flange circumscribing said base plate and having a recess through which the bolt works, and tumblers arranged adjacent the other face of said base plate and controlling the projection and retraction of said bolt, a rotatable controlling element, and a stem operatively connecting said controlling element and said tumblers and extending through the slot in said shank.

6. In a permutation lock, a base plate, a bolt having a head and a shank, the shank being of less thickness than the head and having a projection which over-hangs the head at one side of the shank and between which and said head a clearance intervenes, a spring for retracting the bolt, said spring having a part which projects into said clearance and is engaged with said projection, and a plate forming a part of the lock casing and against which the said head and projection bear.

In testimony whereof I have hereunto set my hand in presence of two subscribing witnesses.

BUELL S. BURNETT.
